UNITED STATES PATENT OFFICE

114,284

DESIGN FOR A DRESS ENSEMBLE

David Klein, New York, N. Y.

Application February 27, 1939, Serial No. 83,215

Term of patent 3½ years

To all whom it may concern:

Be it known that I, David Klein, a citizen of the United States, residing in New York city, in the county of New York and State of New York, have invented a new, original, and ornamental Design for a Dress Ensemble, of which the following is a specification, reference being had to the accompanying drawing, forming part thereof.

Fig. 1 is the front view of a dress ensemble showing my design;

Fig. 2 is the rear view thereof.

Fig. 3 is a front view of the dress of the ensemble, shown in Fig. 1, and

Fig. 4 is the rear view of the dress, shown in Fig. 3.

I claim:

The ornamental design for a dress ensemble, substantially as shown.

DAVID KLEIN.
